United States Patent Office.

CHARLES E. MILLER, OF INDIANAPOLIS, INDIANA.

Letters Patent No. 79,142, dated June 23, 1868.

IMPROVEMENT IN WASH-BOILERS.

The Schedule referred to in these Letters Patent and making part of the same.

TO WHOM IT MAY CONCERN:

Be it known that I, CHARLES E. MILLER, of Indianapolis, Marion county, Indiana, have invented a new and useful Wash-Boiler; and I hereby declare the following to be a full, clear, and exact description thereof, reference being had to the accompanying drawings, making part of this specification.

This is an improvement in those portable wash-boilers which contain provisions for a more effective circulation of the boiling water than takes place in the open boiler, and consists in an arrangement of parts, whereby, firstly, a constant stream or streams of boiling water are projected upon the upper part of the clothes, and are forced through the same by the combined agencies of hydraulic and atmospheric pressure, and whereby, secondly, the discharging-nozzles of said streams can be so adjusted in direction as to strike any desired part or portion of the clothes.

It is well known that fluids in motion have their greatest velocity at the axes of their conduits, and more particularly so in pots or kettles set upon a stove, and receiving their chief heat at the middle of their bottoms. This tendency is found in practice so considerable as to seriously interfere with the effective action of those wash-boilers in which an artificial circulation is attempted, by currents ascending at or near the sides of the vessel, and it is to insure such artificial circulation that the first or main part of my invention is chiefly designed.

Another defect in boilers having such artificial circulation is seen in the excessive action upon those parts of the clothing which receive the full impact of the jet or stream of boiling water, while other parts remain insufficiently acted upon, and the second part of my invention is designed, by the provision of adjustable nozzles, to enable the operator to direct the stream to any or all parts of the clothes, without endangering the scalding of her hands in the attempt to manipulate the clothes themselves.

Figure 1 is a partially-sectionized side elevation of a wash-boiler embodying my invention.

Figure 2 is a top view of such a wash-boiler, from which a portion of the bottom proper has been removed.

The body, A, of my boiler is of the usual oblong form, adapted to occupy two openings of a customary cook-stove.

The bottom proper, B, instead of being flush with the lower edges of the body, is situated slightly higher, so as to remove it from direct contact with the stove or fire.

Attached to and depending from the bottom, B, are two drops or pits, C, which are of such size and position as to enter and occupy the customary boiler-openings of a stove, but which differ from customary pits in that they do not communicate directly with the lower part of the boiler-space, other than through a few apertures, b, in the bottom.

Extending obliquely across the drop, from the lower and inner angle to the upper and outer angle thereof, is a conical or other plate, D, called by me the directing-plate.

Perforations d in this plate are provided, of number or size sufficient to permit the descending current of water to pass below it, but not sufficient to interfere with the design and tendency of said plate to forcibly direct the water occupying the pit, and highly heated by direct exposure to the fire, to rise, by its comparative levity, to the open apex d', and, ascending the pipe E, to escape in the form of jets from the spouts F.

In the preferred form of my improvement, as shown, the pipe E terminates in two elbows, e e', to each of which a spout is so fitted as to be capable of adjustment in the manner shown by dotted lines in fig. 1, so as to enable the operator to direct the streams to any desired part.

The descent of the water in that part of the pit above the directing-plate D, together with the comparative coolness of that part, causes a partial vacuum to take place in its upper part, which coacts with the pressure of air and water above, to force the latter through the meshes of the clothes.

I am aware that portable wash-boilers have before been provided with perforated false bottoms, deflecting-plates, and tubes or conduits, through which water is conducted from the space beneath the false bottom and delivered on top of the clothes. Such an invention therefore I do not claim.

I claim herein as new, and of my invention—

A portable wash-boiler, having the elevated and perforated bottom B, from which depend pits C, having the oblique and perforated directing-plates D, in combination with pipe E and adjustable spout or spouts F, substantially as set forth.

In testimony of which invention, I hereunto set my hand.

CHARLES E. MILLER.
